OTTO SCHUENEMANN
INVENTOR

BY *Victor J. Evans*

ATTORNEY

WITNESS:

G. W. Gandy

UNITED STATES PATENT OFFICE

OTTO SCHUENEMANN, OF NEW YORK, N. Y.

WATCHMAN'S CLOCK

Application filed August 29, 1927. Serial No. 216,210.

This invention relates to improvements in watchmen's clocks.

The primary object of the invention resides in a watchman's clock of the kind to be mounted upon the inside of a door and by which the visits of a watchman may be recorded and in which is embodied an automatic means for recording the time of the actuation of the door lock by an authorized 10 person having a key or by an unauthorized person making a forced entrance by jimmying the lock.

Another object of the invention is to provide a watchman's clock having a recording 15 chart for recording the time of the visit of a watchman thereto, and on which chart, the time of closing and opening of the door to which it may be attached is also recorded.

A further object of the invention is the provision of a time lock recorder in which a time 20 chart is punched by the actuation of the lock bolt to an extended and retracted position.

With these and other objects in view, the invention resides in certain novel construction and combination and arrangement of parts, the essential features of which are hereinafter fully described, are particularly pointed out in the appended claims, and are illustrated in the accompanying drawing, in 30 which:—

Figure 1 is a rear elevation of a door with my invention applied thereto.

Figure 2 is a front elevation of the same.

Figure 3 is an elevational view of the recording instrument with the cover in an open position.

Figure 4 is a vertical transverse sectional view on the line 4—4 of Figure 2.

Figure 5 is a vertical sectional view on the line 5—5 of Figure 4.

Figure 6 is a perspective view of the lock bolt per se.

Figure 7 is a detail perspective view of the key actuated pinion.

45 In carrying my invention into practice, I make use of a suitable casing 10 which includes a body portion 11 for the reception of any suitable well-known form of time pieces or mechanism wherein is included an hour hand or arbor 12 actuated in the customary

manner by a gear train 13. The body of the casing is provided with a swinging cover 14 held in a closed position by a key controlled lock 15 for preventing opening of the cover by an unauthorized person. 55

Within the body portion 11 of the casing 10 is a frame 16 which acts as a support for the works of the time piece employed in connection with this invention. The frame also includes a plate 17 which constitutes a writing table whose office I will describe hereinafter.

The hour hand arbor has a disk 18 secured thereto and as shown, said disk carries a plurality of dial retaining spurs 19 adapted to penetrate a paper dial 20 and hold the same in position to rotate with the arbor whereby in effect, the dial acts as an hour hand. A removable nut 21 is threaded to the end of the arbor shaft 12 for clamping the paper disk 20 against the disk 18. This dial or chart 20 is divided by suitable concentric circles into an outer record bearing portion 22 and an inner record bearing portion 23, each of a type capable of being punctured, mutilated or otherwise suitably marked by a record or actuating instrument or scribe. The dial is divided radially as at 24 by lines 25 which extend from the inner concentric circle to the outer edge of the dial, each radial line being indicative of one-half an hour while every other line is identified by a numeral indicative of an hour, whereby the space between each numeral represents one hour of time. 80

The casing 10 is to be secured to a swinging door 26 by means of attaching lugs 27 and securing elements in the nature of screws 28. In this manner, the casing may be arranged upon the inside of the door as illustrated in Figure 1 of the drawings. Co-acting with the permanent markings of the dial 20 and fixed within the casing 10 is a pointer 29. Under this pointer are sliding spurs or punch rods 30 and 31, the former being slidable through the frame 16 and through an opening 32 in the door 26. The free end of this spur is exposed from the outside of the door and is adapted to be actuated by a night watchman or authorized person 95

so as to move the spur through the aperture 33 in the plate 17 and through an adjacent section of the inner concentric portion 23 of the dial. The metal wear plate 34 is applied to the outside of the door about the opening 32 to prevent wearing away of the door by the constant insertion of the punch key carried by the watchman. The dial underlies the pointer 29 and the spurs 30 and 31 are positioned to co-act with the pointer when punching the dial. The spur 30 is provided with a collar or shoulder 35 which normally holds a pointer 36 of the spur in a retracted position. Likewise the spring holds the outer end of the spur in position where it may be reached by a suitable controlling key, not shown. The spur 30 and its adjuncts constitute a mechanism for marking the inner concentric portion of the dial.

The mechanism for marking the outer concentric portion of the dial consists of the aforesaid spur 31 whose point 37 is adapted to move through an aperture 38 in the plate 17. The outer end of the spur extends into a housing 39 within which a lock bolt 40 is slidably mounted and which lock bolt is movable to a position beyond the outer side of the casing 10 for reception in a keeper 41 mounted on the door jamb. The lock bolt 40 has its top side edge cut-away to provide a cam 42, there being concave recesses 43 on opposite sides of the high spot of the cam. The outer end of the spur 31 is normally held within one of the recesses 43 by a spring 44 which bears against a collar 45 mounted on the spur. The body of the lock bolt is slotted as at 45', the top wall of which is provided with a rack bar 46 for co-acting engagement with a pinion 47 fixed to the end of a stub shaft 48 which extends rearward from the barrel 49 of a key actuated lock mechanism 50. The lock 50 is mounted in the door 26, while the stub shaft 48 extends through the frame 16 and has its bearing in the housing 39.

In the operation of the lock recording mechanism, it will be seen that when a key is inserted in the lock 50 and given a turn, the barrel of the lock will turn and cause the pinion 47 to extend the lock bolt into the keeper 41, by reason of its co-action with the rack bar 46. During this movement of the lock bolt to an extended position, the high spot of the cam 42 will force the spur 31 toward the dial 20 and which spur leaves an impression or puncture upon the dial by reason of the pointed end 37 and which marking will appear in the outer concentric field 22. The same operation occurs when the lock bolt is moved to a retracted position, thus a record will be left upon the dial during each actuation of the lock 50 to record the time of exit and entrance through the door. Should an unauthorized person attempt to force an entrance by jimmying the lock bolt, the time

of said forced entrance will be duly recorded on the dial or chart.

The paper disk 20 is applied to the arbor shaft 12 to present the face of the same outward, whereby the punch rods 30 and 31 penetrate the disk from the rear side, thus causing a raised or embossed work on the face of the same. This assures an easy and accurate reading of the punch marks.

What is claimed as new is:

1. A lock recorder comprising in combination with a casing having a revolvable dial therein, key actuated lock mechanism including a slideable lock bolt, a cam on said bolt, there being recesses in the latter to form said cam, a punch rod having one of its terminals disposed in one of said recesses, the other end of said rod disposed adjacent said dial, and spring means urging said first terminal into said recess, whereby on sliding said bolt said cam is effective to urge said rod against the action of said spring for punching said dial, substantially as and for the purpose described.

2. A lock recorder comprising in combination with a casing having clockwork mechanism therein, a perforable dial on one side of said casing and revolvable by said mechanism; key actuated lock mechanism having a barrel on the other side of the casing, a turnable shaft partly disposed in said casing, a lock bolt slidably mounted within the casing and movable by said shaft; a cam on said bolt, the latter having a recess therein on each side of said cam, a punch rod having one of its terminals in said recess, the other terminal of said rod disposed adjacent said dial, and spring means urging said first terminal into said recess, whereby on actuation of said lock mechanism to turn said shaft said cam is effective, on sliding movement of said bolt, to urge said second terminal, against the action of said spring, into contact with said dial for punching the latter to show the time of actuating the lock mechanism.

In testimony whereof I have affixed my signature:

OTTO SCHUENEMANN.
